UNITED STATES PATENT OFFICE.

CHARLES JOHNSON, OF MINNEAPOLIS, MINNESOTA, ASSIGNOR OF ONE-HALF
TO ARTHUR R. ROGERS, OF MINNEAPOLIS, MINNESOTA.

MACHINE FOR SECURING TOGETHER BOARDS BY MEANS OF CLEATS.

SPECIFICATION forming part of Letters Patent No. 707,116, dated August 19, 1902.

Application filed April 15, 1902. Serial No. 102,972. (No model.)

To all whom it may concern:

Be it known that I, CHARLES JOHNSON, a citizen of the United States, residing at Minneapolis, in the county of Hennepin and State 5 of Minnesota, have invented certain new and useful Improvements in Machines for Securing Together Boards or Strips by Means of Cleats; and I do hereby declare the following to be a full, clear, and exact description of the 10 invention, such as will enable others skilled in the art to which it appertains to make and use the same.

My present invention has for its object to provide a simple and efficient machine for 15 securing together boards or strips by means of cleats; and to this end it consists of the novel devices and combinations of devices hereinafter described, and defined in the claims.

20 The utilization of small strips and boards has become an important problem in the manufacture of lumber. By properly securing together small boards or strips they may be used in lieu of comparatively large boards, 25 and in this way their market value may be greatly increased. Otherwise stated, small pieces or strips of lumber which would otherwise be sold as fuel or at a very low price when secured together to form blanks or 30 large pieces become useful for making boxes and for various building purposes and may be sold for a relatively much higher price.

It is the purpose of my present invention to provide a machine for automatically putting 35 together these strips or relatively small boards to form blanks or composite boards of the above character.

An automatic machine for accomplishing the above result is illustrated in the accompanying drawings, wherein like characters 40 indicate like parts throughout the several views.

Figure 1 is a plan view of the complete machine. Fig. 2 is what may be termed a left 45 side elevation of the machine, some parts thereof being broken away. Fig. 3 is a transverse vertical section taken on the line $x^3 x^3$ of Fig. 1, some parts being left in full. Fig. 4 is a transverse vertical section on the line 50 $x^4 x^4$ of Fig. 1, some parts being left in full. Fig. 5 is a transverse section taken on the

line $x^5 x^5$ of Fig. 4. Fig. 6 is a detail in side elevation, showing the adjustable - throw crank-disk for imparting movements to the blank-feeding plunger or blade; and Fig. 7 55 is a vertical section taken approximately on the line $x^2 x^2$ of Fig. 1.

All of the parts of the machine are supported directly or indirectly from a heavy rectangular frame 1, provided on its top with 60 a horizontally-extended face-plate 2.

All of the running parts of the machine are driven either directly or indirectly from a counter-shaft 3, mounted in suitable bearings on the frame 1 and provided with pulleys 4, 5, and 6. Motion is imparted to the said counter-shaft from a power-driven belt (not shown) which runs over the pulley 4. The pulley 5 has a very wide face and is, in fact, in the form of a drum. A belt 7 runs 70 over the pulley 6 and over a relatively large pulley 8 on a counter-shaft 9, also suitably mounted in bearings on the frame 1. This counter-shaft 9 has a spur-pinion 10, which meshes with the spur-gear 11 on a counter-shaft 12, also suitably mounted in bearings 75 on the frame 1. The counter-shaft 12 is provided at one end with a sprocket 13, and approximately at the center of the machine it is provided with a crank-disk 14, having a 80 variable throw-crank, constructed as herein-after described. A sprocket-chain 15 runs over the sprocket 13 and over a similar sprocket 16, carried at one end of a cam-actuating shaft 17, mounted in suitable bearings 85 18 on the frame 1, as best shown in Fig. 4. The shaft 17 carries a pair of profile-cams 19, having inwardly-projecting cam-surfaces 20, set in line with each other, for a purpose which will be hereinafter noted. 90

A pair of laterally-spaced and vertically-disposed saw-spindles 21 are mounted at the central portion of the machine in bearing-brackets 22. The bearing-brackets 22 are adjustable laterally and transversely of the machine on an upper guide-rod 23 and on a lower guide-bar 24, which rod and bar are rigidly supported at their ends by the sides of the machine-frame, as best shown in Fig. 3. The right-hand bearing-bracket 22 is adapted to 95 be adjusted laterally and held where set by means of an adjusting-screw 25, swiveled in 100

one side of the frame 1 and working with screw-threaded engagement through the upper end of said bracket. The other bearing-bracket 22 is likewise made adjustable and 5 adapted to be held where set by an adjusting-screw 26, which is longer than the screw 25, but which works in the same manner—that is, is swiveled in one side of the frame 1 and works with screw-threaded engagement 10 through the said left-hand bracket 25, directions being here taken with respect to Fig. 3. Each saw-spindle 21 is provided with a small pulley 27, over which and the driving pulley or drum 5 one of a pair of twisted belts 28 15 runs to impart motion to the said spindle. At their upper ends the spindles 21 are provided with thick saws or groove-cutters 29, which work in the same horizontal plane. The strips or board-sections z , which are to 20 form the blanks, are piled in a stack upon the rear portions of a pair of parallel tracks or guide-rails 22^a and within a suitable magazine afforded by a pair of parallel boards or magazine-plates 30, provided with lateral 25 strips 31. The guide-rails 22^a are rigidly secured one to each adjustable bracket 22 and are adjustable with the respective brackets. The forward or inner strips 31 terminate short 30 of the guide-rails 22^a, so as to permit the bottom or lower blank or boards which are to make up the same to be fed forward. The rear or outer strips 31 are secured for lateral 35 adjustments toward and from the forward strips by slot-and-bolt engagements 32. The magazine-plates 30 are shown as secured one to each guide-rail 22^a by brackets 33. The blanks are fed forward one at a time from the bottom of the stack contained in the magazine 30 31 by means of a reciprocating blade 40 or feed-plunger 34, which is carried by a slide 35, which, as shown, works in a dovetailed seat formed in the face of the plate 2. The slide 35 is provided with a longitudinal slot 36, in which is adjustably secured, by means 45 of a nut 37, the stem of a depending head 38. The head 38 is connected by a link 39 to the upper end of a lever 40, the lower end of which is pivoted to an extension 41 of the frame 1. The intermediate portion of the lever 40 is 50 connected by a link 42 to a wrist-pin 43, projected from a block or base 44, which works adjustably in a radial slot 45 of the variable-throw crank-disk 14. The block 44 is adapted to be adjusted and held where set by means 55 of an adjusting-screw 46, swiveled in the face of the said disk 14. When the incomplete blanks are fed rearward out of the magazine, they pass under a gravity-actuated presser-board 47, the forward end of which is pivoted 60 between the side boards 30 of the magazine by means of a rod 48. As the said blanks are moved under the upturned pivoted end of the presser-board 47 they are tightly held downward on the guide-rails 22^a and are forced between and past the saws or cutters 29. The 65 saws or cutters form grooves in the cross-grained edges of the blanks, as best indicated

in Fig. 3. To prevent the saws or cutters from throwing the blanks or the boards thereof backward toward the supply-magazine 70 when the feed plunger or blade 34 is making its return stroke, the said presser-board 47 is provided with gravity-pressed dogs or toothed pawls 49, which engage the said board with a ratchet action. 75

Rearward of the saws or cutters 29, but forward of the rear ends of the rails 22^a and presser-board 47, is a pair of laterally-spaced magazines, which are adapted to contain the cleats z' , arranged in two stacks. These 80 magazines are preferably formed by two pairs of vertically-disposed angle-guides 50, turned with their grooved edges inward and located one pair on each side of the presser-board 47. A pair of parallel laterally-spaced side boards 85 51 coöperate with the angle-irons 50. The boards 51 are secured one to each rail 22^a by means of angle-straps 52. The angle-guides 50 are adjustably secured to the boards 51 by slot-and-bolt engagements 53. (Best shown 90 in Fig. 2.) The cleats z' are piled in stacks within the magazines afforded by the angle-guides 50 and coöperating boards 51, as best shown in Figs. 2 and 4. The bottom members of the cleats z' of each stack are adapted 95 to be fed simultaneously inward by blades or feed-plungers 54, carried by slides 55, which, as shown, work with dovetailed engagements in seats 56, formed in the face-plate 2, as best shown in Figs. 4 and 5. The 100 slides 55 are provided with slots 57, in which are adjustably secured, by means of suitable nuts, the stems of studs 58, on the depending ends of which are mounted rollers 59. The rollers 59 are subject to the cams 19 and are 105 adapted to be engaged and moved simultaneously inward by the cam-surfaces 20 of the said cams. Normally the slides 55 and rollers 59 are held far enough outward to carry the 110 driving blades or plungers 54 outward of the stacks or cleats z' , so that the bottom members of the said cleats will normally rest upon the faces of the rails 22^a. The said slides are 115 yieldingly held outward or in their normal positions preferably by weights 60, suspended by cords 61, passed over the guide-sheaves 62 and connected to the rear ends of reversely-acting levers 63, the other ends of which levers press against the nuts 58' of the roller-equipped studs 58. As shown, the guide-sheaves 62 are mounted on suitable projections from the rear end of the face-plate 2, and the levers 63 are pivoted at 63' to the top of the said face-plate 2. 120

The operation of the machine, briefly summarized, is as follows: At each reciprocation of the blank-feeding blade or plunger 34 an unfinished blank z , made up of several boards or sections, will be fed rearward under the presser-board 47 and past the saws or groove-cutters 29, under which movement the grooves will be cut in the ends of the same, as already described. A second movement of the said blade or plunger 34 will of course force out 125

- another or second blank, and this second blank will force the first or preceding blank into a position where its grooved ends will stand between and in line with the lower cleats z' of the two stacks contained in the magazines 50 51. While the said plunger 34 is making its return stroke the said aligned blank will be left standing still, and during this time the cam-surfaces 20 of the cams 19, 10 acting on the rollers 29 of the slides 55, force inward said slides, together with the blades 54, thereby causing said blades to force inward the lower members of the two stacks of cleats z' and tightly press the same into the grooved 15 ends of the several boards of the aligned blanks. The cleats are thus caused to securely unite the several boards or strips of the blank, and when they are thus applied the blanks are put into commercial form.
- 20 It will be seen that the cleat-feeding blades or plungers 54 operate simultaneously to press the cleats into the opposite grooved edges of the blank and react the one against the other. Otherwise stated, the one blade serves as a 25 stop to hold the blank while the other blade is pressing the cleat into place in the grooved edge of the blank, and the said relation is reciprocal between the said blades or cleat-pressing devices.
- 30 The action above described is of course under the continued operation of the machine automatically repeated over and over again, while the completed blanks will be crowded rearward and dropped from the rear ends of 35 the tracks 22^a and face-plate 2.

From the description already given it will of course be understood that by properly adjusting the several magazines and by properly adjusting the movements of the blank-feeding and cleat-feeding plungers or blades 40 blanks or composite boards of any desired size, within certain limits, of course, may be made by the machine described. It will also of course be understood that when one 45 of the saw-guides 22 is adjusted laterally the corresponding magazine-plates 30 and 51 will be moved therewith. The said magazine-plates may be made adjustable with respect to the guide-rails 22^a, which carry them, so as 50 to compensate for the wear of the saws or cutters. It is not of course necessary that both of the brackets 22 be made adjustable, but it is desirable in that the capacity of the machine for holding large blanks is thereby 55 increased.

I have demonstrated the efficiency of the machine above described by actual usage of the machine for the purposes set forth.

It will of course be understood that the 60 machine described is capable of many modifications within the scope of my invention as herein set forth and claimed.

What I claim, and desire to secure by Letters Patent of the United States, is as follows:

- 65 1. The combination with a pair of groove-cutters, of means for feeding the blanks edge-

wise between said cutters to groove the opposite edges thereof, and a pair of pressing devices for pressing the cleats into the opposite grooved edges of said blank, which pressing 70 devices react the one against the other, substantially as described.

2. The combination with means for feeding the grooved blanks, of means for supplying cleats to the opposite grooved edges of said 75 blanks, and a pair of pressing devices for pressing into said grooved edges of the blanks, which pressing devices react the one against the other, substantially as described.

3. The combination with a pair of laterally-spaced magazines for the cleats, of means for feeding the grooved blanks between said magazines, and reversely-reciprocating feed plungers or blades coöperating with said magazines and serving to press said cleats into 85 the grooves of said blanks, substantially as described.

4. The combination with a pair of laterally-spaced magazines for the cleats, of means for feeding the grooved blanks between said 90 magazines, a pair of reversely-movable cleat-feeding plungers or blades, and means for simultaneously moving said plungers inward, involving a counter-shaft and a pair of cams, carried thereby, substantially as described. 95

5. The combination with a pair of laterally-spaced magazines for the cleats, one of which magazines is adjustable laterally with respect to the other, of means for supplying the grooved blanks between said adjustable 100 magazines, and reversely-movable cleat-feeding plungers or blades coöperating with said magazines and serving to press the cleats into the grooves of said blanks, substantially as described.

6. The combination with a laterally-adjustable magazine for the blanks, of means for feeding said blanks, one at a time, from said magazine, and a pair of laterally-spaced cleat-supplying magazines between which said 110 blanks are fed, and reciprocating blades or plungers for pressing the cleats into the grooved edges of said blanks, substantially as described.

7. The combination with a magazine for 115 the blanks, and means for feeding the blanks, one at a time, from the magazine, a cutter for grooving an edge of said blank as the same is fed from the magazine, and a cleat-supplying magazine past which the grooved 120 edge of said blank is moved, and means for pressing the cleats from said magazine into the grooved edge of said blank, substantially as described.

8. The combination with a blank-supplying mechanism, and means for feeding the blanks therefrom, one at a time, of a pair of saws or cutters between which said blanks are fed edgewise of a pair of cleat-supplying magazines between which said blanks are fed, 130 after passing said cutters, and means for pressing said cleats into the opposite grooved

edges of said blanks, substantially as described.

9. The combination with a blank-supplying magazine and a reciprocating blank-feeding plunger or blade, of a pair of saws or cutters for grooving the edges of the blanks as they are fed from the magazine, a pair of laterally-spaced cleat-supplying magazines between which the grooved blanks are fed, and a pair of reversely-reciprocating plungers or blades for simultaneously pressing the cleats into the opposite edges of the blanks, substantially as described.

10. The combination with a blank-supplying magazine and means for feeding the blanks therefrom, one at a time, of a pair of laterally-spaced magazines for the cleats, means for pressing the cleats into the grooves of said blanks, and a pivoted gravity-held presser-board extending from said blank-supplying magazine between said cleat-maga-

zines, and under which the blanks are caused to pass, substantially as described.

11. The combination with a pair of supports extending in the general direction of the feed of the machine, one of said supports being adjustable laterally with respect to the other, of an adjustable blank-supplying magazine, the sides of which are mounted one on each of said supports, means for feeding the blanks, one at a time, from said magazine, a pair of laterally-spaced cleat-magazines mounted one on each of said supports, and means for pressing the cleats from said cleat-magazines into the grooved edges of the blanks, substantially as described.

In testimony whereof I affix my signature in presence of two witnesses.

CHARLES JOHNSON.
